H. F. CLAYTON

FUEL BURNER

Filed July 20, 1925

FIG.1.

FIG.2.

Inventor
Harry F. Clayton
By
John W. Allen
Attorney

UNITED STATES PATENT OFFICE.

HARRY F. CLAYTON, OF STRATHMORE, QUEBEC, CANADA, ASSIGNOR TO HERBERT BARTHOLOMEW, OF MONTREAL, CANADA.

FUEL BURNER.

Application filed July 20, 1925. Serial No. 44,650.

This invention relates broadly to improvements in burners for fluid fuel and more particularly to burners for liquid fuel such as oil; and the object of the invention 5 is to provide a burner of the injector or atomizer type designed to be supplied with a motive fluid under pressure, such as steam or air, for the purpose of drawing the fuel into the burner by suction and atomizing 10 the fuel to facilitate combustion thereof.

A further object is to provide a burner of simple, inexpensive and durable construction which may be readily cleaned and which will not require adjustment.

15 Various other objects and the advantages of the invention may be ascertained from the following description.

The burner comprises inner and outer parts, the inner part having channels for 20 passage of fuel and motive fluid, and the outer part uniting with the inner part to form a Venturi outlet.

25 In the accompanying drawings which illustrate the preferred embodiment of the invention but to the precise details and proportions of which the invention is not of necessity confined;—

Fig. 1 is a central horizontal longitudinal section of the burner.

30 Fig. 2 is a central longitudinal vertical section of the burner.

Referring more particularly to the drawings, 11 designates a short body portion, 35 preferably cylindrical in form, having at its forward end an externally threaded portion 12 of somewhat less diameter, which in turn carries at its forward end a portion 13 of still further reduced diameter whereby shoulders 14 and 15 are formed. The 40 free end of the part 13 is tapered at 16 very nearly to a point. The three parts 11, 12 and 13 are co-axially arranged and provided with a cylindrical bore 17 common to all three parts, which extends from the back 45 end of the part 11 to approximately the commencement of the taper 16 and is thereafter sharply tapered to a very small bore 18, which extends through the end of the part 13. A lateral passage 19 internally threaded 50 for the connection of a supply pipe communicates with the bore 17, and the rear end of the bore is closed by a screw plug 20 or other suitable device which may be removed

upon occasion for the purpose of cleaning out the bores 17 and 18.

A second bore 21 is provided parallel with the bore 17 and extending from the shoulder 15 nearly to the back end of the part 11. An inlet passage 22 internally threaded for connection of a supply pipe 60 leads preferably at an angle to the axis of the burner into the rear end of the bore 21. Preferably the axes of the passages 19 and 22 are located at an angle of 90° apart, so that when the passage 22 is at the top of the burner the passage 19 is at one side.

A cap or nozzle 23 is provided, being internally screw-threaded at its rear end to screw on the part 12 and abut the shoulder 14. This cap is provided with an internal shoulder 24 to be spaced some distance in front of the shoulder 15. Beyond the threaded portion, the cap is provided with a bore 25 sufficiently larger in diameter than the part 13 to form an annular space 70 into which the passage 21 opens. The forward end of this passage is tapered at substantially the same angle as the tapered part 16 and of such dimensions that when the cap is in position a narrow annular passage 75 26 is formed between the two tapered surfaces. The tapered bore of the part 23 extends slightly beyond the end of the part 13. From the end of the tapered bore to the end of the cap, the bore diverges or flares, as shown at 27, the angle of divergence being preferably the same as the angle of convergence.

The two parts of the burner are assembled, as shown in the drawings, and a motive fluid supply pipe connected to the inlet 90 19 and the fuel supply pipe connected to the inlet 22. In certain installations, it is preferable to arrange the burner with a downward inclination and it is for this purpose that the fuel inlet 22 is arranged at an angle to the axis of the burner, as shown, but it will be understood that this angular arrangement and the angular distance apart of the passages 19 and 22 are not essential 95 to the operation of the burner but may be modified according to the position in which the burner is to be mounted and according to other requirements of the installation. Where the burner is to be downwardly inclined as already stated, it is convenient to 100 105

arrange the fuel inlet 22 at the top or bottom, so that a vertically arranged pipe may support the burner at the desired angle of inclination.

5 The operation of the burner is extremely simple. Motive fluid, such as compressed air or steam is admitted to the passage 17 and escapes through the reduced outlet 18 at very high velocity. The rush of the fluid 10 through the small end of the tapered bore 25 produces a suction in the annular passage 26, which serves to draw fuel through the passages 21 and 22 and through a supply pipe from any suitable source. The 15 natural cone of dispersal of the motive fluid substantially fills the reduced end of the bore 25, so that fuel drawn through the annular passage 26 is finely divided or atomized and very intimately mingled with the 20 motive fluid.

Having thus described my invention, what I claim is:—

1. A fluid fuel burner comprising a body shouldered to form a rear part, a smaller 25 externally threaded intermediate part and a still smaller front part, tapering at its forward end, a motive fluid passage extending axially through all three body parts and reduced in diameter at its forward end, a 30 fuel passage parallel with the first passage opening through the front shoulder of the body, an internally shouldered cap taper bored in front of its shoulder and screwed in rear of its shoulder on the intermediate 35 part of the body, the cap shoulder and front body shoulder being spaced and forming an annular channel into which the fuel passage opens and the bore of the cap being slightly larger than the front part of the body, there-

by to form a narrow tapering annular passage communicating with the first annular passage for egress of fuel. 40

2. A fluid fuel burner comprising a body shouldered to form a rear part, a smaller externally threaded intermediate part and a 45 still smaller front part tapering at its forward end, a motive fluid passage extending axially from the rear end through all three body parts and reduced in diameter at its forward end, a plug in the rear end of said 50 passage giving access for cleaning without dismounting the burner, a fuel passage parallel with the first passage opening through the front shoulder of the body, an internally shouldered cap taper bored in front of its shoulder and screwed in rear of its shoulder on the intermediate part of the body, the cap shoulder and front body shoulder being maintained in spaced relation by engagement of the rear end of the cap and 55 the rear shoulder of the body, such spacing forming an annular channel into which the fuel passage opens and the bore of the cap being slightly larger than the front part of the body thereby to form a narrow tapering 60 annular passage communicating with the first annular passage for egress of fuel, the bore of the cap being flared beyond the end of the body and at substantially the same angle as the taper, and radial inlet passages 65 for the motive fluid and fuel passages arranged approximately 90° apart, the fuel inlet passage being additionally inclined toward the front of the burner. 70

In witness whereof, I have hereunto set 75 my hand.

HARRY F. CLAYTON.
